UNITED STATES PATENT OFFICE

152,013

DESIGN FOR A FURNITURE BASE OR SIMILAR ARTICLE

George H. Mildwoff, New York, N. Y.

Application March 15, 1947, Serial No. 137,635

Term of patent 3½ years

(Cl. D33—1)

To all whom it may concern:

Be it known that I, George H. Mildwoff, a citizen of the United States of America, residing in New York city, county of New York, and State of New York, have invented a new, original, and ornamental Design for a Furniture Base or Similar Article, of which the following is a specification, reference being had to the accompanying drawing, forming part thereof, wherein the figure is a perspective view of a furniture base, showing my new design.

I claim:

The ornamental design for a furniture base or similar article, substantially as shown.

GEORGE H. MILDWOFF.
